UNITED STATES PATENT OFFICE.

HENRY O. SCHMIDT, OF NEW YORK, N. Y., ASSIGNOR TO SIMONS, BROTHERS & CO., OF PHILADELPHIA, PENNSYLVANIA.

DESIGN FOR A CANE OR UMBRELLA HANDLE.

SPECIFICATION forming part of Design No. 20,561, dated March 3, 1891.

Application filed February 6, 1891. Serial No. 380,520. Term of patent 3½ years.

To all whom it may concern:

Be it known that I, HENRY O. SCHMIDT, a citizen of the United States, residing in New York, in the county and State of New York, 5 have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

The shank A extends upwardly and terminates in a crook or arm B on the one hand 15 and an upwardly-extending point C on the other. The entire shank portion A and the portions B and C are ornamented by a series

of ribs E F, formed of plain and rough work alternately, substantially as shown. The bottom part of the shank A is mounted by a 20 band D, which may be highly ornamented.

The handle may be made of any suitable material.

Having now described my new design, what I claim as new, and desire to secure by Letters 25 Patent, is—

The design for cane or umbrella handles, substantially as herein described and shown.

In testimony of which invention I have hereunto set my hand.

HENRY O. SCHMIDT.
